UNITED STATES PATENT OFFICE.

LUCIUS PERSON, OF HOLYOKE, MASSACHUSETTS.

AUTOMATIC ANIMAL-FEEDER.

SPECIFICATION forming part of Letters Patent No. 448,256, dated March 17, 1891.

Application filed May 31, 1890. Serial No. 353,780. (No model.)

To all whom it may concern:

Be it known that I, LUCIUS PERSON, a citizen of the United States, residing at Holyoke, Hampden county, State of Massachusetts, 5 have invented a new and useful Automatic Animal-Feeding Mechanism, of which the following is a specification.

My improvements relate to the construction of feed-retaining boxes above the mangers and to the details of mechanism connecting said boxes with an alarm-clock, so that at a predetermined time the feed may be discharged into the mangers, the objects of my improvements being to simplify the 15 construction and operation of such mechanism and facilitate its combination with the ordinary alarm-clock; and my invention consists in the combination and construction as hereinafter described, and more particularly 20 pointed out in the claim.

My invention is fully illustrated in the accompanying drawings, in which—

Figure I is an elevation, in partial section, of two feed-boxes, with cords therefrom 25 to a clock. Fig. II is a top plan view of the clock. Fig. III is an enlarged rear elevation of the clock. Fig. IV is an enlarged side view of the clock with the combined winding-key and cord-pulley detached, and Fig. V is a 30 plan view of one feed-box.

In the drawings, A is the alarm-clock now in general use, having upon its rear side, in addition to the main winding-key *a*, an alarm-winding key *h*. The key *h* is made 35 detachable, and with its stem is combined a pulley *i* for winding a cord *m*. This is more particularly shown in Fig. IV, and it will be seen that by this construction any slack in the cord, owing to stretching or to hygro- 40 metric causes, can be taken up upon the pulley before fixing it upon the shaft *o* of the alarm, and also that the increased winding-surface afforded by the pulley over the usual key-stem permits cord enough to be taken up 45 to provide for an extended movement of the free ends of the doors *H H*, to which the cord *m* is attached.

To the cord *m* is fastened the ends of cords *n n*, which are conducted, as shown in Fig.

I, through an eye *p*, through eyes *r* in the 50 sides of the boxes *I I*, through holes in the boxes to eyes *s* in the free ends of doors *H H*, and from thence, if more boxes are used, through holes *t* to the doors *H H* of said boxes. These cords *n n*, uniting in the cord *m*, are 55 wound in the act of winding the alarm to close the doors *H H* to retain the feed which may be placed in the boxes to rest upon said doors, and upon the springing of the alarm, without intermediate mechanism from the 60 alarm-shaft *o* to the boxes *I I*, the boxes are free to empty themselves by gravity.

The clock A can be detached in a few moments for use in the dwelling and be replaced with equal loss of time. 65

As shown in the drawings, the doors *H H* are arranged in the boxes *I I* to form inclined bottoms thereto when closed, so as to cause the contents to act as a wedge in starting and swinging the doors upon their hinges when 70 released by their cords *n n*, and I arrange a flexible hood *c* to project from the inside of the boxes over the joint formed by the hinged end of the doors with the side of the boxes, which protects said joint from being filled up 75 by the feed.

In Fig. I the hood is shown in profile in both positions, the dotted line indicating that position taken by the hood in covering the distended edge of the depressed door. 80

In Fig. V the strip, preferably of leather or canvas, is shown tacked to the inside of the box *I* to leave a lower edge free to lap over the door *H*.

The surfaces of the holes adjacent to the 85 eyes *s* of the doors, and the eyes *r* and *p*, through which the cords *n n* pass at an angle, support a large portion of the weight of the feed upon the closed doors *H H*, so that no more weight is applied through cord *m* to 90 pulley *h* than the alarm-shaft and mechanism connected therewith can easily carry.

I am aware that it is not new to use clock mechanism in stables for regulating the time of feeding, and make no claim to any principle controlling the same; but 95

What I claim is—

In an automatic feed-box for animals, the

combination of a winding-key *h* and cord-winding pulley *i*, combined and adapted to be made fast to the alarm-winding shaft of a clock, a cord *m*, secured to pulley *i*, cords *n* 5 *n*, attached to cord *m*, eyes *p* and *r* for guiding cords *n n*, and doors *H H*, hinged in boxes *I I* and inclined therein to have their lower

free edges attached to cords *n n*, passing thereto through the wall of the boxes, all operating as and for the purpose set forth.

LUCIUS PERSON.
